UNITED STATES PATENT OFFICE.

WILLIAM O. BUNNELL AND QUINCY A. GATES, OF WILKES-BARRE, PENNSYLVANIA.

GARBAGE-RECEPTACLE.

1,239,427.

Specification of Letters Patent. Patented Sept. 4, 1917.

Application filed December 8, 1916. Serial No. 135,876.

To all whom it may concern:

Be it known that we, WILLIAM O. BUNNELL and QUINCY A. GATES, citizens of the United States, and residents of Wilkes-Barre, in the county of Luzerne, State of Pennsylvania, have invented certain new and useful Improvements in Garbage-Receptacles, of which the following is a specification.

10 The present invention relates to the class of metallic shipping and storing vessels and has particular reference to new and useful improvements in garbage receptacles.

The primary object of our invention is 15 to provide a new and improved type of garbage receptacle which has means associated therewith to prevent the obnoxious odors therefrom interfering with the person desiring to deposit garbage in the said receptacle.

Another object of our invention is to provide a garbage receptacle having a novel type of closure which may be opened only when a partition separating the garbage 25 receptacle from a housing formed therein is in closed position.

A still further object of our invention resides in the provision of a device of the character described that is simple in construction, efficient in operation, and that can be manufactured and placed on the market at a minimum cost.

Other objects as well as the nature, characteristic features and scope of our garbage 35 receptacle will be more readily understood taken in connection with the accompanying drawing, and pointed out in the claims forming a part of this specification, in which:

Figure 1 is a side elevational view of a 40 garbage receptacle embodying the improvements of our invention; and

Fig. 2 is a vertical sectional view taken on the line 2-2 of Fig. 1.

Fig. 3 is a fragmental detailed view showing the strip as attached to the door.

Referring more particularly to the drawing, wherein similar characters of reference designate like and corresponding parts throughout the various views, 1 designates 50 the body of our improved garbage receptacle, the same having the usual bottom 2 therein. The body of the receptacle is open at the upper end and is provided with a conical closure 3 hinged at 4 to the peripheral wall of the body. A locking hasp 5 is pivotally connected as at 6 to the said coni-

cal closure, the hasp having a common opening therein adapted to engage a staple 7 secured to the body of the garbage closure. The hasp, of course, when the lock is removed from the staple provides a handle 60 for opening the said closure means.

A supplemental opening is provided in the peripheral wall of the body 1 adjacent the upper free end thereof, said opening 65 being closed by a curved door 8 and mounted in a guide frame 9 carried by the upper frame of the said body 1. A sliding partition 10 forms a bottom for a housing designated H in its entirety. A handle 11 is 70 pivotally connected to the outer or exposed end of the partition 10 to withdraw the partition 10 when the door 8 is in closed position.

A strip of metal 12 is soldered or secured 75 in some other suitable manner to the door 8. The said strip 12, and metallic laterally extending flange 13 formed from the bottom of the partition 10 provides the guiding means for the lower edge of the sliding 80 curved door 8. The strip 12 also provides a means for preventing the withdrawal of the sliding partition when the door is in open position as best shown in Fig. 3. A plurality of L-shaped lugs 14 are mounted on 85 the rear end of the partition 10 to limit the rearward movement of the same. The handle 15 is mounted on the sliding curved door to facilitate opening and closing of the same. A vertical flange 16 formed on 90 the peripheral wall of the body limits the sliding movement of the door when the same is being closed. When the sliding door has been opened and has passed beyond the flange 13 it engages a supplemental flange 95 18 formed in alignment with the said flange.

In operation when it is desired to insert garbage within the receptacle the sliding door 15 is opened and the garbage deposited on the partition 10. The sliding door is 100 closed and the partition 10 is withdrawn by means of the handle 11. During this operation it is of course obvious that the garbage deposited on the partition will be removed therefrom and deposited in the body 1. 105

We desire to lay particular stress upon the fact that none of the obnoxious gases generated in such receptacles would nauseate the persons depositing the garbage in the receptacle as the supplemental housing and the partition 10 serve to retain the said 110 gases in the body of the receptacle.

From the above description taken in connection with the accompanying drawing, it can be easily seen that we have provided a device that is simple in construction, containing but a few simple parts that can be cheaply manufactured and assembled and when assembled can be placed upon the market and sold at a minimum cost.

It will be understood that the above description and accompanying drawing comprehend only the general embodiment of our garbage receptacle and that various minor changes in details of construction, proportion and arrangement of the parts may be made within the scope of the appended claims without sacrificing any of the advantages of our invention.

Having thus fully described our invention, what we claim as new and desire to secure by Letters Patent, is:—

1. In a garbage receptacle, the combination of a body having an opening therein, a sliding door forming a closure for said opening, a housing formed in the said body, a sliding partition forming a bottom for said housing, and means associated with the said door preventing withdrawal of the partition when the door is in open position.
2. In a garbage receptacle, the combination of a body having an opening therein, a housing formed in the said body registering with the said opening, a sliding partition forming a bottom for the said housing, a sliding door forming a closure for the said

opening, and a strip formed on the said door adjacent one end thereof to prevent opening of the partition when said door is open.

3. In a garbage receptacle, the combination with a body having an open end, a conical closure for said open end, a housing mounted in the said body adjacent the upper end thereof, the said body having an opening therein registering with the said housing, a sliding partition forming a bottom for the said housing, a sliding door forming a closure means for the last mentioned opening, and means associated with the said partition to open the same when the sliding door is in closed position.

4. In a garbage receptacle, the combination of a body having an opening therein adjacent the upper end of said body, a housing formed within the said body registering with the said opening, a sliding partition forming a bottom for the said housing, a plurality of L-shaped lugs formed on one end of the partition for limiting the movement of the same, on the free end of the said partition a laterally extending flange is provided, and a sliding door forming a closure means for the said opening being adapted to slide on said flange.

In testimony whereof, we affix our signatures hereto.

WILLIAM O. BUNNELL,
QUINCY A. GATES.
